UNITED STATES PATENT OFFICE.

RUDOLPH HOFFMAN, OF CLEVELAND, OHIO.

BURNER.

Application filed April 8, 1926. Serial No. 100,639.

This invention relates to oil burners and more especially to the wick-type of burner adapted for use in stoves.

It is one of the objects of the invention 5 to provide a simple and inexpensive form of locking device for the flame-spreader unit, such device to be capable of locking the flame-spreader unit so that it may not be lifted by the wick.

10 A further object of the invention is to provide an improved and inexpensive supporting means for the outer collar of the burner.

Other objects of the invention and the 15 features of novelty will be apparent from the following description, taken in connection with the accompanying drawings of which Fig. 1 is a partial elevation and partial section of a burner embodying my invention.

Fig. 2 is an elevation of the flame-spreader unit, detached from the burner.

Fig. 3 is an elevation of the outer collar, with a portion thereof broken away to show 25 the interior supporting lugs.

Fig. 4 is a bottom plan of the outer collar.

Fig. 5 is a plan view of one of the devices by which the outer collar is supported.

Fig. 6 is a plan view of the inner latch 30 ring which co-operates with the flame-spreader unit.

Fig. 7 is a side elevation of the latch ring, with a part shown in section.

Referring to the drawings 10 indicates 5 the wick tube which is formed by concentrically arranged tubes that are separated to provide space for the usual annular wick 11. A circumferential ledge 12 is provided on the exterior wick tube 10 for the purpose of supporting the outer collar 13. Arranged within the collar 13, at the lower end thereof, there are a plurality of arcuate strips or members 14 having their ends turned radially inward as indicated at 15 to form lugs 45 which engage with the ledge 12 and thus support the collar on the latter. The members 14 are preferably spot-welded to the collar 13 as this forms a very simple convenient and inexpensive mode of attachment.

50 There is a ledge 16 on the interior of the wick tube for supporting the flame-spreader unit which comprises the disc 17 and a plurality of wings 18, the latter being secured to the under side of the disc 17 and having their lower edges 19 resting on the

ledge 16. In the construction illustrated there are four radially extending wings 18 and each of these is provided with a perforation 20, adjacent the lower end thereof, which is adapted to be engaged by one of 60 the hook-like projections 21 on the ring 22, this ring having an up-standing flange, which carries the projections 21, and a horizontally extending flange 23 which is secured under the side of the ledge 16. Adjacent each of the projections 21 there is a recess 24 adapted to receive the lower end of one of the wings 18 so that the projections 21 may engage with the perforations 20 by a slight rotation of the flame-spreader unit. 70

From the foregoing it will be seen that when the projections 21 engage with the perforations 20 the flame-spreader unit will be locked in position and held against being lifted by the engagement of the wick 11 75 with the periphery of the disc 17. At the same time the flame-spreader unit may be readily detached from the wick tube by a slight rotation to disengage the projections 21 from the perforations 20, after which the 80 unit may be lifted out of the wick tube. For convenience in doing this the flame-spreader unit may be provided with a bail 25 which extends through the disc 17 and has its lower ends spot-welded to two of the wings 18, as 85 shown at 26.

Having thus described my invention, what I claim is:

1. In oil burners, the combination of a plurality of concentric tubes having a space 90 for an annular wick therebetween, a removable flame-spreader comprising a disc and wings secured to the under side of the disc and having their edges fitting the inner of said tubes, means for supporting the flame-spreader, a ring secured within said inner tube and provided with a plurality of hook-like projections, and said wings having perforations adapted to be engaged by said projections by rotating the wick-spreader 100 on its supporting means.

2. In oil burners, the combination of a plurality of concentric tubes having a space 105 for an annular wick therebetween, a removable flame-spreader comprising a disc and wings secured to the under side of the disc and having their edges fitting the inner of said tubes, a circular ledge on the interior of the said inner tube and adapted to be engaged by the lower edges of said wings to 110

support the flame-spreader, a ring having an up-standing flange provided with a plurality of horizontally extending hook-like projections, and said wings having perforations adapted to be engaged by said projections by rotating the flame-spreader on said ledge.

3. In oil burners, the combination of a wick tube having an external circumferential ledge, a collar surrounding said wick tube and spaced therefrom, and a plurality of arcuate members secured to the interior of said collar and having radially extending

wings adapted to engage said ledge and thereby position and support said collar. 15

4. In oil burners, the combination of a wick tube having an external circumferential ledge, a collar surrounding said wick tube and spaced therefrom, and a plurality of arcuate members secured to the interior 20 of said collar and having their ends turned radially inward to engage and thereby position and support said collar.

In testimony whereof, I hereunto affix my signature.

RUDOLPH HOFFMAN.
